UNITED STATES PATENT OFFICE.

WARREN P. FREEMAN, OF NEW YORK, N. Y.

COMMUTATOR FOR DYNAMO-ELECTRIC MACHINES.

SPECIFICATION forming part of Letters Patent No. 313,489, dated March 10, 1885.

Application filed March 10, 1884. (No model.)

To all whom it may concern:

Be it known that I, WARREN P. FREEMAN, of the city, county, and State of New York, have invented a new and useful Improvement in Commutators for Dynamo-Electric Machines; and I hereby declare the following to be a full and clear description thereof.

This invention relates to an improved construction of the cylindrical drum or body of the commutator, and the arrangement on and attachment of the commutator-strips thereto, and will be readily understood by the accompanying drawings, of which—

Figure 1 is a sectional elevation of the improved commutator, taken on the line *x x* of Fig. 3. Fig. 2 is an end elevation of the commutator. Fig. 3 is a sectional plan of it, taken on the line *y y* of Fig. 1. Figs. 4 and 5 are respectively a sectional elevation of the bushing for insulating the screw and the screw used for attaching the commutator-strips to the cylindrical drum.

The central or body part of the commutator consists of a drum or cylinder, *A*, which has a hub, *a*, through which its driving - shaft passes, and an annular flange, *a'*, at each side of it at the periphery.

The commutator-strips *B* are placed transversely on the outside or periphery of the cylinder *A*, and secured thereto by means of screws *C*, passing through the flanges *a'*, and threaded in the said commutator - strips. Each of the said screws in passing through the flange *a'* is surrounded by an insulating-bushing, *D*, made of some suitable insulating material—such as hard rubber, for instance. Each of the said bushing-pieces has a flange at its inner end, as shown clearly in Fig. 4, the said flange resting against the inner face of the flange *a'* of the drum when the parts are assembled, as shown in the other figures of the drawings. An annular strip or sheet, *E*, of hard rubber or other insulating material, is interposed between the periphery of the drum *A* and the surrounding commutator-strips *B*, and an insulating-strip, *F*, of a like material, is interposed between each two adjacent edges of the commutator-strips. By means of these insulators and the screw-bushings *D* the commutator-strips are perfectly insulated, and the said commutator-strips are held firmly to the periphery of the

drum *A* by means of the screws *C*, one screw in each end of each commutator-strip. 55 The said screws being threaded in the pieces *B*, and placed radially through the flanges *a'*, with the heads of the screws placed inwardly toward the hub of the commutator, the parts are held firmly together without any liability to displacement of the commutator-strips or the production of cross-currents resulting therefrom. The heads of the screws *C* being placed inwardly toward the hub of the commutator, there are no perforations or obstructions on the outsides of the commutator-strips, the holes for the said screws not extending through the said strips; consequently there are no peripheral impediments to the continuous and perfect action of the machine. 70

In one end of each of the commutator-strips *B* there is inserted a metallic screw, *G*, with a washer, *H*, under its head, for the attachment of the wires leading from the dynamo 75 through the dynamo-shaft in a manner well known.

Having described my invention, I claim—

1. A commutator for a dynamo-electric machine, having the commutator-strips placed 80 transversely on the periphery of the commutator drum or cylinder, and secured thereto by means of retaining-screws passing radially through peripheral flanges at the sides of the said drum, the screws threaded in the said 85 commutator - strips, and placed with their heads toward the hub of the said drum or cylinder.

2. A commutator for a dynamo-electric machine, consisting of a drum or cylinder, *A*, 90 peripheral commutator - strips *B*, secured thereto by insulated screws *C*, passing radially outward through side flanges, *a'*, at the periphery of the drum or cylinder *A*, and threaded in the said commutator-strips, and 95 insulating - strips *E* and *F*, respectively separating the commutator-strips from the drum or cylinder and from each other.

In testimony whereof I have signed my name to this specification in presence of two sub- 100 scribing witnesses.

WARREN P. FREEMAN.
